UNITED STATES PATENT OFFICE.

ERNEST EMIL KRENGEL, OF BUENA VISTA, OREGON.

CAR-AXLE.

SPECIFICATION forming part of Letters Patent No. 352,761, dated November 16, 1886.

Application filed April 20, 1886. Serial No. 199,457. (No model.)

To all whom it may concern:

Be it known that I, ERNEST EMIL KRENGEL, a citizen of the United States, and a resident of Buena Vista, in the county of Polk and State 5 of Oregon, have invented certain new and useful Improvements in Car-Axes; and I do hereby declare that the following is a full, clear, and exact description of the invention, which will enable others skilled in the art to which 10 it appertains to make and use the same, reference being had to the accompanying drawings, which form a part of this specification, and in which—

Figure 1 is a perspective view of as much 15 of a car-axle as will show my improvement. Fig. 2 is a longitudinal vertical sectional view of the same; and Fig. 3 is a perspective view of the parts of the axle separated.

Similar letters of reference indicate corresponding parts in all the figures.

My invention has relation to that class of 20 axles for railway-cars in which two halves of an axle are journaled at their inner ends in a box for the purpose of admitting of one wheel 25 running at a speed different from the other, as in passing curves and similar places; and it consists in the improved construction and combination of parts of the same, as herein-after more fully described and claimed.

30 In the accompanying drawings, the letters A A indicate the two halves of the axle, which are formed with enlarged heads B, or collars, at their inner ends, having the facing sides rounded. The inner ends of the axle-halves are journaled in a sleeve, C, the middle portion, D, of which is greater in diameter, and formed with thicker walls, than the 35 ends, for the purpose of strengthening the sleeve at its middle; and this enlarged central portion of the sleeve is formed with grooves or channels E E, having perforations F into the axial bore of the sleeve.

A cylindrical box, G, surrounds the sleeve, and fits snugly upon the swelled portion of 45 the same, and one side of this box is provided with an oil-aperture having a neck, H, provided with a screw-cap, I, through which neck and aperture the box may be filled with oil, the heads of the box having apertures in their 50 centers slightly larger than the bore of the sleeve and bearing snugly against the ends of the sleeve, having washers J interposed between them and the ends of the sleeve. Two sleeves or boxings, K K, fit upon the axle-

halves and within the ends of the sleeve, bearing with their inner ends against the collars upon the axle-halves, and the flanges or collars L upon the outer ends of the boxings are secured to the ends of the sleeve by means of screw-bolts M. It will thus be seen that the 55 boxings will confine the axle-halves within the sleeve, while they may revolve within the sleeve and boxings independently of each other, allowing one wheel to run at a speed different from the speed of the other wheel; 60 and the halves of the axle may very easily be taken apart by simply removing the fastening-bolts in the flanges of the boxings, when the boxings and the axle halves may be drawn out of the ends of the sleeve.

The outer cylindrical casing or box serves as a reservoir for oil, which may be filled into the casing through the neck and aperture at the middle of the casing, and, after closing the aperture by the screw-cap, the oil contained 75 in the casing may be distributed through the grooves and apertures in the sleeve to the axle-halves within the sleeve, lubricating them, and the washers at the ends of the sleeve between the said ends and the apertured heads 80 of the outer casing will prevent any of the oil from passing out at the ends of the casing.

The longitudinal grooves in the enlarged central portion of the sleeve will allow the oil 85 to pass to both ends of the sleeve and will 90 guide the flow of the oil to the oiling perforations in the sleeve, and a sufficient quantity of oil may be filled into the casing to lubricate the axle-halves sufficiently for the motion required of them for a considerable length of 95 time.

Having thus described my invention, I claim and desire to secure by Letters Patent of the United States—

The combination of the divided car-axle, 95 the flanged boxings, the centrally enlarged, grooved, and perforated sleeve, the washers, and the outer casing provided with an oil-aperture and serving as an oil-reservoir, substantially as shown and described.

In testimony that I claim the foregoing as my own I have hereunto affixed my signature in presence of two witnesses.

ERNEST EMIL KRENGEL.
